UNITED STATES PATENT OFFICE.

ALFRED A. PEDNEAU, OF MOBILE, ALABAMA.

LOCOMOTIVE SLACK ADJUSTER.

Application filed July 9, 1925. Serial No. 42,482.

To all whom it may concern:

Be it known that I, ALFRED A. PEDNEAU, a citizen of the United States, residing at Mobile, in the county of Mobile and State of Alabama, have invented certain new and useful Improvements in a Locomotive Slack Adjuster, of which the following is a specification.

This invention relates to an improved device which is especially, but not necessarily, adapted to be interposed between a locomotive and an accompanying tender, for the purpose of taking up and eliminating slack, absorbing shocks and jars, and otherwise affording an excellent connection between the locomotive and tender.

It is well known that considerable slack and resultant play exists between the ordinary locomotive and its tender, this permitting objectionable and undue lost motion and resulting in wear and tear on the parts, and particularly upon the draw bars. In fact, the wear is so evident that it is ordinarily compulsory to remove and examine the draw bar after approximately ninety days' use, and to make repairs or replacements wherever necessary. This practice is expensive and is accompanied by a loss of considerable time.

In view of the foregoing objectionable circumstances, I propose to interpose a novel device between the locomotive and tender, connecting the parts of the device with the same in a manner to exert an endwise thrust, to effect a tight coupling, and to eliminate abnormal slack such as ordinarily exists.

An object is, of course, to provide a device wherein the construction is exceedingly simple, inexpensive to manufacture, practical in operation, and such that it can be applied to conventional locomotives and tenders without requiring alterations or interference with the operation of existing details.

The invention is further characterized by a cylinder in which a plunger is forced outwardly under the action of air, the air serving as a cushion to absorb shocks and being supplied from a by-pass leading from the usual train pipes.

In the accompanying drawing forming a part of this application, and in which like numerals are employed to designate like parts throughout the same:

Figure 1 is a side elevation of the coupled ends of a conventional locomotive and tender

showing the improved device in place therebetween.

Figure 2 is an enlarged top plan view of the device showing the parts in operative association.

Figure 3 is a central vertical section through the primary detail of the invention.

Referring to the drawing in detail, it will be seen that the reference character 1 designates a plate which is adapted to be bolted or otherwise rigidly fastened to the under framing of the tender. Formed integral with one face of this plate is a cup 2, which functions as a cylinder. In this connection it will be noted that the upstanding branch 3 of a valved bypass 4 is connected with the bottom of the cylinder and serves to supply air to the same. The valved by-pass is designated by the reference character 4' and I would call attention to the fact that it is preferably in the form of an oil check valve which is arranged to permit the supply of air to the cylinder and to prevent and trap the air in the cylinder and the line in the case of a sudden shock requiring a strong air resistance cushion. The by-pass is coupled in any appropriate manner to the ordinary train pipe 5. Slidable in the cylinder is a hollow piston 6. The piston is of discular design and is provided on its outer end with a rounded protuberance 7. On its inner end it is provided with a central cylindrical boss 8 surrounded by a washer 9 serving to maintain a leather packing ring 10 in place. Small oil ports 11 are bored in the top of the cylinder and closed by removable plugs 12, permitting the wall of the piston to be thoroughly lubricated to facilitate operation.

The inward movement of the piston is limited by the boss 8 striking the plate 1, and it will be noted in Figure 3 that an air chamber is provided between the inner end of the piston and this plate.

Cooperative with the parts already described is what may be generally referred to as an abutment 13. This abutment comprises a flat vertical plate 14, and a right angular attaching flange 15 braced from the plate by a reinforcing web 16. In practice, the abutment is bolted or otherwise secured to the underframe of the engine, and the piston and cylinder secured to the underframe of the tender. The parts are, of course, arranged in the opposed relation as shown in the drawing with the rounded pro-

tuberance 7 bearing against the flat face of the abutment plate. Up to two thousand pounds of air may now be introduced into the cylinder to force the piston outwardly 5 and against the abutment whereby to exert a thrust in opposite directions against the engine and tender to force them away from each other and to take up slack existing in the couplings. The device however is not 10 too rigid, but sufficiently elastic to permit the necessary relative movement between the tender and engine. At the same time, the device functions somewhat as a shock absorber or bumper, and further as a means 15 for eliminating undue rattling of draw bars and the like. In fact, by maintaining the engine and tender in proper relation, much wear is taken off of the parts. Consequently, it is unnecessary to carry on the 20 ninety day examinations of the tender equipment, for, in practice, it has been proved that the life of the car is prolonged to an unusual extent by the presence of this device. This means that the device has been 25 actually made and successfully installed, and has accomplished results beyond expectations.

No doubt, a consideration of the description in connection with the drawings will 30 enable persons familiar with structures of this class to obtain a clear understanding of the invention. Therefore, a more lengthy description is thought unnecessary.

While the preferred embodiment of the

invention has been shown and described, it 35 is to be understood that minor changes coming within the field of invention claimed may be resorted to if desired. For instance, while the description may, offhand, lead one to believe that the invention is to be 40 restricted to a locomotive and tenders, it is not to be so construed, for it is equally well adapted for disposition between coaches and cars, or for other forms of rolling stock. Moreover, the same could be used between 45 motor vehicles.

Having thus described the invention, what I claim as new and desire to secure by Letters Patent is:—

As a new article of manufacture, a 50 pneumatic cushioning and thrust device for connection with the under frame of a locomotive tender comprising a plate formed with an integral cup adapted to function as a cylinder, a valved air supply pipe connected with said cup, a hollow piston slideable in said cylinder, said piston having its outer end formed with a rounded protuberance adapted to contact a buffer plate, and being formed on its inner end with a centrally located boss, and a packing ring surrounding the boss and having fluid tight contact with the wall of said cylinder, said boss being of a length to space the inner end 55 of the piston from the corresponding end of the cylinder.

In testimony whereof I affix my signature.
ALFRED A. PEDNEAU.
